United States Patent Office.

PASCAL P. CHILD, OF ST. LOUIS, MISSOURI.

Design No. 4,293, dated August 16, 1870.

DESIGN FOR A JOURNAL-BOX.

The Schedule referred to in these Letters Patent and making part of the same

I, PASCAL P. CHILD, of St. Louis, in the county of St. Louis and State of Missouri, have invented and produced a new and original Design for an Anti-friction Journal-Box, of which the following is a specification.

Figure 1 is a perspective view of the complete box. Figure 2 shows, in perspective and detached, the three pieces of which the box is composed.

A, the stand, and

B, the roller, constitute the box proper.

At each end of A is a perforated lug, a, for attachment to the frame.

Four vertical standards, a', give side bearing to the shaft that rests upon the top of the roller B, said roller having journal bearing at the foot of the standards.

C is the cap, which is made to fit the top of the box, and is so formed as to carry off gritty water that would otherwise fall upon the journals and cause friction and wear.

The cap has, at each end, a lug, c, which has a recess in its lower side, to receive the lug a, of the stand, and which is perforated in a similar manner, to admit the screw, by which both cap and box are attached to the frame.

The whole forms a very efficient anti-friction box, and, being cast in but three pieces, and having less weight of metal than other anti-friction boxes, is consequently cheaper of production.

I claim as my invention—

1. The conformation of the box or stand A, substantially as represented.
2. The ornamental configuration of the cap C, substantially as represented.

PASCAL P. CHILD.
